APPARATUS FOR COMBUSTION OF FLUID FUEL
WITH OXYGEN

John Blizzard, Garden City, N. Y., assignor to Foster Wheeler Corporation, New York, N. Y., a corporation of New York

Application May 5, 1948, Serial No. 25,212

4 Claims. (Cl. 158—4)

This invention relates to the combustion of fluid fuel and more particularly to the burning of hydrocarbon oil in the presence of oxygen.

The present invention provides an apparatus for the burning of hydrocarbon oil in the presence of oxygen wherein the feeding of oil to the burners of a combustion chamber is controlled in response to the flow of gases of combustion resulting from the burning of an oil-oxygen mixture in an auxiliary combustion chamber and the oil fed to said burners is burned in the presence of oxygen after ignition by the gases from the auxiliary combustion chamber.

In accordance with the present invention oxygen and oil under pressure are introduced into a pressure-tight auxiliary combustion chamber. The amount of oil introduced into said auxiliary combustion chamber being sufficient to heat the oxygen, upon combustion of the oxygen-oil mixture, to a high degree, for example to substantially within the range of 1000° F. to 1500° F. The gases of combustion from the auxiliary combustion chamber are passed through a turbine in which the temperature and pressure of the gases are reduced, said gases thereafter flowing into a main combustion chamber wherein they ignite oil injected into the main combustion chamber through burners. The pump for pumping oil into the burners is actuated by said turbine. When starting the apparatus of the present invention, oxygen under pressure passes from the auxiliary combustion chamber through the turbine and actuates the oil pump thereby pumping oil to the auxiliary combustion chamber. After the oxygen-oil mixture in the auxiliary combustion chamber is ignited, the gases of combustion pass through the turbine and operate the same thereby actuating the pump. Upon passage of combustion gases from the turbine to the main combustion chamber, oil is permitted to enter said main chamber, oil being pumped thereto and to the auxiliary combustion chamber during normal operation in response to the flow of combustion gases from the auxiliary chamber to the main combustion chamber.

The invention will be understood from the following description when considered in connection with the accompanying drawing forming a part thereof and in which:

The single figure is a more or less diagrammatic view partly in section and partly in elevation of the apparatus of the present invention.

Referring to the drawing, oxygen under pressure in a container 10 flows through valved outlet 11 into a line 12 thence through said line into nozzle 13 of a fuel injector or burner 14 to which one end of the line 12 is connected. The injector or burner 14 is associated with a pressure-tight auxiliary combustion chamber 15 and receives oil from conduit 16 which oil together with oxygen is injected into said auxiliary combustion chamber. The oil-gas mixture entering chamber 15 through injector or burner 14 is, as shown, ignited by an electrical igniter 17. Gases of combustion from auxiliary combustion chamber 15 are passed to gas turbine 18 through flue gas conduit 19 which gas actuates said turbine so as to impart movement to drive shaft 20. Drive shaft 20 drives a pump 21 the suction inlet 22 of which is in communication with an oil feed pipe 23. Discharge outlet 24 of pump 21 communicates with feed conduit 25.

As shown in the drawing, feed conduit 25 is in communication with burners 26, 27, and 28 of a steam generator 29 through branch lines 38, 39 and 40 respectively. Lines 38, 39 and 40 are respectively controlled by valves

41, 42 and 43. Steam generator 29 comprises a setting 30 having a combustion chamber 31 therein. The side walls, roof, and hopper bottom of steam generator 29 are lined by tubes 31' which, as shown, are a part of the circulatory system of steam generator 29 and communicate with an upper steam and water drum 32. Burners 26 and 28 receive oxygen from containers 33 which containers have valved outlets 34 in communication with a line 35 through conduits 36. The line 35 is connected to burner 26 while a branch line 37 is in communication at one end thereof with line 35 and at the opposite end with burner 28. Gases from turbine 18 flow through gas conduit 18' to burner 21 and are injected into combustion chamber 31.

Oil entering injector 14 through line 10 is passed into said line from conduit 25 at a point on the discharge side of pump 21.

In operation, when starting the apparatus of the present invention, oxygen under high pressure from container 10 flows through line 12 into injector 14 thence to enter auxiliary combustion chamber 15, pass therethrough and enter conduit 19. From conduit 19, the oxygen flows through turbine 18 operating said turbine to thereby actuate oil pump 21. At this point in the operation of the apparatus, valves 41, 42 and 43 in branch lines 38, 39 and 40 respectively are closed so that oil will not enter main combustion chamber 31. When the pump 21 is actuated by turbine 18 by the flow of oxygen therethrough, oil is pumped from line 25 into line 23 thence into line 16. From line 16, oil enters injector 14, the oxygen-oil mixture thence passing from injector 14 into auxiliary combustion chamber 15 wherein said mixture is ignited by igniter 17 and is burned. The amount of oil introduced into auxiliary combustion chamber 15 is controlled by a valve in line 16 and is sufficient to heat the oxygen, upon combustion of said mixture, to a temperature within substantially the range of 1000° F. to 1500° F. These gases then pass through line 19 into gas turbine 18 so as to actuate said turbine and rotate drive-shaft 20 which sets pump 21 into operation. The temperature and pressure of the gases are lowered in flowing through turbine 18 to a temperature, for example, of 900° F. and to a pressure, for example, of 650 #/sq. inch. The gases at substantially said temperature and pressure then flow through line 18' to burner 21 associated with steam generator 29. Upon flow of gases into combustion chamber 31 from burner 21, valves 41, 42 and 43 are opened so that oil may now flow through branch lines 38, 39 and 40.

Operation of pump 21 by the passage of gases through turbine 18 causes oil to be pumped from line 25 into line 23 and thence into burners 26, 27, and 28 through branch lines 38, 39 and 40 respectively. Oxygen under pressure for burner 26 is supplied from containers 33 through lines 36 and 35 and to burner 28 through lines 36, 35 and 37 respectively.

The heated gas flowing through conduit 18' into combustion chamber 31 through burner 27, which gas comprises oxygen with a smaller amount of carbon dioxide and vapor, ignites oil admitted to combustion chamber 31 through burners 27, 26, and 28. It will be noted that oil is supplied to burners 26, 27, and 28, which fires combustion chamber 31 and steam generator 29, by action of pump 21. Oil, therefore, will not be supplied to the burners of combustion chamber 31 unless gas turbine 18 is operated by the flow of gases from the auxiliary combustion chamber 15 through turbine 18 into line 18'.

In the embodiment of the invention shown wherein oil for the auxiliary combustion chamber 15 is supplied thereto by pump 21 through line 16, when starting it would be necessary to drive turbine 18 initially by oxygen until sufficient combustion gases were generated to operate said turbine. It will be understood that oil may be supplied to auxiliary combustion chamber 15 from a source independent of pump 21 if so desired.

Inasmuch as changes may be made in the form, location and relative arrangement of the several parts of said apparatus without departing from the essential characteristics of the invention, it will be understood that the invention is not to be limited excepting by the scope of the appended claims.

What is claimed is:

1. Apparatus for the combustion of fluid fuel with oxygen which comprises means forming a pressure-tight auxiliary combustion chamber, a source of oxygen constantly under pressure in communication with said chamber, said chamber including fluid inlet means adapted to communicate with a source of fluid fuel, a gas turbine, gas conducting means in communication with the gas turbine and the auxiliary combustion chamber, means forming a main combustion chamber, means for introducing fuel into the main combustion chamber, means for conducting oxygen into the main combustion chamber, other gas conduit means in communication with said turbine and with the main combustion chamber so as to receive gases from the turbine and conduct them to the main chamber, and a pump actuated by said turbine, the pump being in communication with the means for introducing fuel into the main combustion chamber and adapted to communicate with a source of fluid fuel so as to pump said fuel into the main combustion chamber.

2. Apparatus for the combustion of hydrocarbon oil with oxygen which comprises means forming a pressure-tight auxiliary combustion chamber, a container of oxygen constantly under pressure and in communication with said chamber, said chamber including fluid inlet means adapted to communicate with a hydrocarbon oil fuel source, igniting means so associated with the chamber as to ignite a hydrocarbon oil-oxygen mixture therein, a gas turbine, gas conducting means in communication with the gas turbine and the auxiliary combustion chamber, means forming a main combustion chamber, means for introducing hydrocarbon oil into the main combustion chamber, means for conducting oxygen into the main combustion chamber, other gas conduit means in communication with said turbine and with the main combustion chamber so as to receive gases of combustion from the turbine and conduct them to the main chamber, and a pump actuated by said turbine, the pump being in communication with the means for introducing hydrocarbon oil into the main combustion chamber and adapted to communicate with a source of fluid fuel so as to pump said fuel into the main combustion chamber.

3. Apparatus for the combustion of hydrocarbon oil with oxygen which comprises means forming a pressure-tight auxiliary combustion chamber, an injector including fluid inlet means adapted to communicate with a hydrocarbon oil fuel source, a container of oxygen constantly under pressure in communication with the injector, said injector being so associated with the auxiliary combustion chamber as to inject said oxygen and hydrocarbon oil fuel into the chamber, igniting means so associated with the chamber as to ignite a hydrocarbon oil-oxygen mixture therein, a gas turbine, gas conducting means in communication with the gas turbine and the auxiliary combustion chamber, means forming a main combustion chamber, a plurality of other injectors, fuel conduit means in communication with each of said plurality of other injectors, com-

5 bustion gas conduit means in communication with at least one of said other injectors and with said turbine so as to receive gases of combustion from the turbine and conduct them to the main chamber, means for conducting oxygen to the injectors other than said at least one injector, said other injectors being so associated with the main combustion chamber as to inject fuel and gas thereinto, and a pump actuated by said turbine, the pump being in communication with the fuel conduit means and adapted to communicate with a source of hydrocarbon fuel so as to pump said fuel into the main combustion chamber.

10 4. Apparatus for the combustion of hydrocarbon oil with oxygen which comprises means forming a pressure-tight auxiliary combustion chamber, an injector, a container of oxygen constantly under pressure in communication with the injector, said injector being so associated with the auxiliary combustion chamber as to inject said oxygen and hydrocarbon oil fuel into the chamber, a hydrocarbon oil fuel line in communication with the injector, igniting means so associated with the chamber as to ignite a hydrocarbon oil-oxygen mixture therein, a gas turbine, gas conducting means in communication with the gas turbine and the auxiliary combustion chamber, means forming a main combustion chamber, a plurality of other injectors, fuel conduit means in communication with each of said plurality of other injectors, flow control means in said fuel conduit means for controlling the flow of fuel to said other injectors, gas conduit means in communication with one of said other injectors and with said turbine so as to receive gases from the turbine and conduct them to the one injector, means for conducting oxygen to the injectors other than said one injector, said other injectors being so associated with the main combustion chamber as to inject fuel and gas thereinto, and a pump actuated by said turbine, the pump having an outlet in communication with said fuel conduit means and having fluid inlet means adapted to communicate with a source of hydrocarbon fuel so as to pump said fuel from said source into the main combustion chamber, the pump outlet also being in communication with said hydrocarbon oil fuel line so that fuel is pumped to said auxiliary combustion chamber.
